FIGURE 1 is a top plan view of a refrigerator defroster or similar article, showing my new design;

FIGURE 2 is a side elevational view thereof;

FIGURE 3 is a bottom plan view thereof;

FIGURE 4 is an end elevational view thereof;

FIGURE 5 is an enlarged fragmentary vertical sectional view taken along line 5—5 of FIGURE 1;

FIGURE 6 is an enlarged fragmentary vertical sectional view taken along line 6—6 of FIGURE 1; and

FIGURE 7 is an enlarged fragmentary vertical sectional view taken along line 7—7 of FIGURE 1.

The conventional electrical cord fragmentarily shown in FIGS. 1, 2 and 3 is broken away for convenience of illustration.

I claim:

The ornamental design for a refrigerator defroster or similar article, substantially as shown and described.
